UNITED STATES PATENT OFFICE

140,459

DESIGN FOR A SINGLE PLACE TANK

Joseph J. Baldine, Hubbard, Ohio

Application July 27, 1942, Serial No. 107,719

Term of patent 14 years

(Cl. D14—3)

To all whom it may concern:

Be it known that I, Joseph J. Baldine, a citizen of the United States, residing at Hubbard, in the county of Trumbull and State of Ohio, have invented a new, original, and ornamental Design for a Single Place Tank, of which the following is a specification, reference being had to the accompanying drawings, forming part thereof.

I claim:

The ornamental design for a single place tank, as shown.

JOSEPH J. BALDINE.
